[57] CLAIM

The ornamental design for a carton, substantially as shown.

DESCRIPTION

FIG. 1 is a front perspective view of a carton showing our new design;
 FIG. 2 is an end elevational view;
 FIG. 3 is a bottom view;
 FIG. 4 is a rear elevational view;
 FIG. 5 is a perspective view of the carton in open position; and
 FIG. 6 is a view similar to FIG. 5 showing the half not seen in FIG. 5.

*FIG. 1.**FIG. 2.**FIG. 3.**FIG. 4.*FIG. 5.

FIG. 6.
